CLAIM

The ornamental design for a body supported holder, as shown and described.

DESCRIPTION

FIG. 1 is a top, front and side environmental perspective view of a body supported holder showing my new design, the portion of the figure shown in broken lines representing a user of the design, electronic device, and support straps for the design, and forming no part of the claimed design;

FIG. 2 is a bottom plan view thereof;

FIG. 3 is a top plan view thereof;

FIG. 4 is a rear elevational view thereof;

FIG. 5 is a front elevational view thereof;

FIG. 6 is a right side elevational view thereof; and,

FIG. 7 is a left side elevational view thereof.

FIG. 1

FIG. 2

FIG. 3

FIG. 4

FIG. 5

FIG. 6

FIG. 7
